UNITED STATES PATENT OFFICE.

WILLIAM C. DOHERTY, OF ALBANY, OREGON.

FRUIT-DRIER.

SPECIFICATION forming part of Letters Patent No. 245,797, dated August 16, 1881.

Application filed May 24, 1881. (No model.)

To all whom it may concern:

Be it known that I, WILLIAM C. DOHERTY, of Albany, in the county of Linn and State of Oregon, have invented certain new and useful 5 Improvements in Fruit-Driers; and I do hereby declare that the following is a full, clear, and exact description of the invention, which will enable others skilled in the art to which it appertains to make and use the same, reference 10 being had to the accompanying drawings, which form a part of this specification.

Figure 1 is a perspective view of my improved fruit-drier, parts of the frame or casing being broken away in order to show the construction. Fig. 2 is a vertical sectional view. Fig. 3 is a vertical section on the line xx , Fig. 15 2; and Fig. 4 is a horizontal sectional view.

Corresponding parts in the several figures are denoted by like letters of reference.

20 This invention relates to fruit-driers; and it consists in certain improvements in the construction of the same, which will be herein-after fully described, and particularly pointed out in the claim.

25 In the drawings hereto annexed, A represents a suitable casing, consisting, essentially, of a square bottomless box provided at or near its lower end with flanges B, and with a curved or Ω -shaped partition, C, to distribute and 30 radiate the heat from the furnace, upon which the drier is in practice to be placed. Vertical slides or dampers D are provided near the lower end of casing A. The sides E E of the casing A are provided upon the inside with 35 vertical bars, F, having upward and outward projecting spring-brackets G. Adjoining the said bars F are fitted vertically-sliding bars H, which are also provided with upward and outward projecting spring-brackets I. The lower 40 guides, J, are arranged, as shown, to form shelves on a level with the bottom of the front door or opening, K, with which the device is provided.

45 Journaled in the upper end of the box or casing are a pair of rock-shafts, L, having crank-arms M, to which the sliding bars H are connected by means of straps or pitmen N. The said shafts are also provided with cranks

O connected by a pivoted rod, P, so that an oscillating motion imparted to one of the shafts 50 shall be instantly communicated to the other. One of the shafts L is provided outside the casing with a band-wheel or crank, Q, by which it may be conveniently operated.

Shelves or trays R, made of wire-cloth, perforated metal, or in any other suitable manner, 55 are to be employed in connection with my invention.

From the foregoing description, taken in connection with the drawings hereto annexed, the 60 operation and advantages of my invention will be readily understood.

A tray filled with pared and sliced (or otherwise properly prepared) fruit being placed upon the bottom shelves, J, the shafts L may be operated by the cranks, thus causing the spring-brackets I of the vertically-sliding bars H to lift the said tray up upon the lowermost of the brackets G of bars F. In the same manner each successive tray may be lifted or elevated, 70 step by step, from the bottom to the top of the casing, thus giving to each tray of fruit the benefit of the gradually-increasing heat from the bottom to the top of the drier.

Having thus described my invention, I claim 75 and desire to secure by Letters Patent of the United States—

As an improvement in fruit-driers, the combination, with the herein-described casing A, having suitable means for radiating the heat, 80 and vertically-sliding bar mechanism for elevating the trays step by step from the bottom of the box, of the rock-shafts L, journaled in the upper end of the casing, having crank-arms M, to which the vertically-sliding elevating-bars 85 are connected by a pitman, N, and cranks O, connected by the pivoted rod P, all arranged and operating substantially as herein shown and specified.

In testimony that I claim the foregoing as 90 my own I have hereto affixed my signature in presence of two witnesses.

WILLIAM C. DOHERTY.
